(57) **CLAIM**

The ornamental design for a surgical stapler deck with tissue engagement recess features, as shown and described.

DESCRIPTION

FIG. 1 is an enlarged perspective view of a surgical stapler deck with tissue engagement recess features, showing our new design;

FIG. 2 is a front elevational view of the surgical stapler deck of FIG. 1;

FIG. 3 is a rear elevational view of the surgical stapler deck of FIG. 1;

FIG. 4 is a first side elevational view of the surgical stapler deck of FIG. 1;

FIG. 5 is a second side elevational view of the surgical stapler deck of FIG. 1;

FIG. 6 is a top plan view of the surgical stapler deck of FIG. 1; and,

FIG. 7 is a bottom plan view of the surgical stapler deck of FIG. 1.

The broken lines in the drawings depict portions of the surgical stapler deck with tissue engagement recess features and form no part of the claimed design.
